(57) **CLAIM**

The ornamental design for the golf training device, as shown and described.

DESCRIPTION

FIG. 1 is a front isometric view of a golf training device showing my new design, shown with a slidable canister in

an upper-shaft position, and a retractable line shown in an extended and clipped position;

FIG. 2 is a front, elevation view of the golf training device of FIG. 1, shown with the slidable canister in the upper-shaft position, and a retractable line shown in the extended and clipped position;

FIG. 3 is a rear, elevation view of the golf training device of FIG. 1, shown with the slidable canister in the upper-shaft position, and a retractable line shown in the extended and clipped position;

FIG. 4 is a left side elevation view of the golf training device of FIG. 1, shown with the slidable canister in the upper-shaft position, and a retractable line shown in the extended and clipped position;

FIG. 5 is a right side elevation view of the golf training device of FIG. 1, shown with the slidable canister in the upper-shaft position, and a retractable line shown in the extended and clipped position;

FIG. 6 is a top, plan view of the golf training device of FIG. 1, shown with the slidable canister in the upper-shaft position, and a retractable line shown in the extended and clipped position;

FIG. 7 is bottom, plan view of a set of golf training device of FIG. 1, shown with the slidable canister in the upper-shaft position, and a retractable line shown in the extended and clipped position;

FIG. 8 is a front isometric view of the golf training device of FIG. 1, shown with the slidable canister in the upper-shaft position, and the retractable line shown in a retracted position;

FIG. 9 is a front, elevation view of the golf training device of FIG. 1, shown with the slidable canister in the upper-shaft position, and the retractable line shown in the retracted position;

FIG. 10 is a rear, elevation view of the golf training device of FIG. 1, shown with the slidable canister in the upper-shaft position, and the retractable line shown in the retracted position;

FIG. 11 is a left side elevation view of the golf training device of FIG. 1, shown with the slidable canister in the upper-shaft position, and the retractable line shown in the retracted position;

(Continued)

FIG. 12 is a right side elevation view of the golf training device of FIG. 1, shown with the slidable canister in the upper-shaft position, and the retractable line shown in the retracted position;

FIG. 13 is a top, plan view of the golf training device of FIG. 1, shown with the slidable canister in the upper-shaft position, and the retractable line shown in the retracted position; FIG. 14 is bottom plan view of a set of golf training device of FIG. 1, shown with the slidable canister in the upper-shaft position, and the retractable line shown in the retracted position;

FIG. 15 is a front isometric view of the golf training device of FIG. 1, shown with the slidable canister in a lower-shaft position, and the retractable line shown in a retracted position;

FIG. 16 is a front, elevation view of the golf training device of FIG. 1, shown with the slidable canister in a lower-shaft position, and the retractable line shown in the retracted position;

FIG. 17 is a rear, elevation view of the golf training device of FIG. 1, shown with the slidable canister in a lower-shaft position, and the retractable line shown in the retracted position;

FIG. 18 is a left side elevation view of the golf training device of FIG. 1, shown with the slidable canister in a lower-shaft position, and the retractable line shown in the retracted position;

FIG. 19 is a right side elevation view of the golf training device of FIG. 1, shown with the slidable canister in a lower-shaft position, and the retractable line shown in the retracted position;

FIG. 20 is a top, plan view of the golf training device of FIG. 1, shown with the slidable canister in a lower-shaft position, and the retractable line shown in the retracted position; and, FIG. 21 is bottom plan view of a set of golf training device of FIG. 1, shown with the slidable canister in a lower-shaft position, and the retractable line shown in the retracted position.

The features shown in broken lines in the drawing depict portions of the design that form no part of the claimed design.
